[57] CLAIM

The ornamental design for a bulk garbage bag dispenser, as shown and described.

DESCRIPTION

FIG. 1 is a front elevational view of a bulk garbage bag dispenser showing my new design, the broken-line disclosure of a roll of garbage bags being for illustrative purposes only and forming no part of the claimed design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

FIG. 1

FIG. 2

FIG. 3

FIG. 4

FIG. 5

FIG. 6
